EXTRUSION OF CLAY PRODUCTS

John F. Booth and Rowland K. Smith,
Hazlehead, near Sheffield, EnglandApplication November 17, 1949, Serial No. 127,936
In Great Britain November 26, 1948

16 Claims. (Cl. 25—22)

1

This invention relates to the extrusion of clay products in machines of the type in which the clay is fed to the top of a cylinder and forced downwardly to an extrusion orifice by means of a worm.

One object of the invention is to provide for the feeding of clay to the cylinder in accordance with the rate at which clay is extruded. A further object is to maintain the clay in the cylinder substantially constant at the amount producing the greatest extrusion efficiency. Yet another object is to provide for the feeding of a battery of machines from a common supply. Other objects will appear from the following description.

According to the present invention, the feed of clay to an extrusion cylinder is controlled by forming a substantially level surface on the body of clay to be extruded and varying the rate of feed of clay to the body in accordance with variations in the level of said surface, more clay being fed as the surface falls in response to extrusion so as to restore the level.

By "substantially level" is meant that the surface as a whole is flat, as quite distinct from the approximate vortex produced by the rotation of the clay; but in practice the surface is not and need not be truly flat, and minor variations from true flatness permit a sufficiently sensitive and accurate control to be made.

It is generally convenient if the fall in the surface below a predetermined level permits the feeding of more clay to the body, and the consequent rise to another predetermined level cuts off the feeding, the limits of rise and fall in the surface being kept within the greater amount of clay that would result in overloading the machine and the lesser amount of clay that would not adequately pack the extrusion worm.

In mechanism according to the invention, the substantially level surface is formed on the body of clay to be extruded by at least one arm adapted to be rotated about the axis of the cylinder, and the rate of feed of clay to the body is varied in accordance with the movement of a feeler member adapted to rise and fall in response to variation in the level of the surface.

The arm is preferably formed with an upstanding blade, the arm generally sweeping the clay to a level and the blade removing from the wall of the cylinder the layer of clay forming there as a vestige of the vortex-like surface tending to be produced by the rotation of the clay as a whole. Advantageously, more than one arm and blade are used, the arms and blades conveniently being inclined so as to assist in urging the clay downwardly.

2

The feeler member is preferably formed with a pair of feelers to provide two surfaces of contact with the clay, and the movement of the feeler member preferably serves to operate a servo-mechanism operated by mechanical, pneumatic, hydraulic or electrical means, or combinations of such means, serving to control the amount of clay fed to the cylinder, the clay being continuously fed in an amount equal to the maximum requirement of the machine and the particular requirement at any moment being diverted to the machine in response to the action of the feeler member, the excess being returned to be fed again. The feeler member is conveniently pivoted above the level of the surface in the cylinder.

The invention will now be described in greater detail, by way of example, with reference to the accompanying drawings, in which

20 Figure 1 is a diagram illustrating the automatic feeding of clay to a battery of four machines;

25 Figures 2 and 3 are a sectional elevation and plan, respectively, of the upper portion of one of the extrusion presses diagrammatically illustrated in Figure 1;

30 Figure 4 is side elevation, drawn to a smaller scale than Figures 2 and 3, showing the feeding of clay to the hopper of the press shown in Figures 2 and 3;

35 Figures 5 and 6 are, respectively, a front elevation and plan of part of the apparatus shown in Figure 4;

Figure 7 is an elevation of the upper portion of an extrusion press showing a modified form of feed hopper;

40 Figure 8 is a diagram illustrating the control circuit of the apparatus shown in Figures 2 to 6; and

45 Figure 9 is a diagram illustrating the control circuit of the apparatus shown in Figure 7.

Referring first to Figure 1, a battery of four extrusion presses 11, 12, 13 and 14 are fed with clay from a common mixing plant 16, the clay being delivered from the mixing plant 16 in "shredded" form (i. e., in relatively small pieces or particles) on to a main belt conveyor 17 which delivers the clay to a chute 18 leading to a feed conveyor 19 leading to the four presses in succession. The clay is fed from the mixing plant 16 in an amount at least equal to the maximum requirement of the four presses 11 to 14 and the particular amount required by each press is diverted to a chute 21, leading to the feed hopper 55 of the press, by one of a series of ploughs 22, the first plough being set to move over one quarter

of the belt width, the next over one half of the width, the third over three quarters of the width and the last over the whole width. Each plough 22 thus normally sweeps into its chute a quarter of the clay fed by the conveyor belt 19.

The ploughs 22 are automatically moved into operative or inoperative position in accordance with the requirements of the presses, as will be described later, and any surplus of clay not swept off the belt 19 by the last plough is discharged into a chute 23 leading to a return conveyor 24 which, in turn, discharges into a return chute 26 leading back to the main conveyor 17. The operator in charge of the mixing plant 16 regulates the supply of clay from the plant in accordance with the amount of scrap being returned by the conveyor 24.

A continuous feed of clay is thus provided to the battery of presses, each press automatically diverting from the conveyor 19 sufficient clay for its own needs. The manner of control of the clay feed to the individual presses will now be described.

Referring to Figures 2 and 3, an extrusion worm 31 housed in an extrusion cylinder 32 is driven by a bevel pinion 33 mounted on a drive shaft 34 and arranged in mesh with a bevel gear 36 secured to the shaft 37 of the worm 31, the shaft 37 being provided with an upper bearing in a bearing bracket 38 secured to an enlarged upper portion 39 of the cylinder 32 constituting a feed chamber, the bearing bracket 38 serving also to house bearings for the drive shaft 34.

Clay is fed into the feed chamber 39 from a feed hopper 41 by an oscillating charger 42 pivoted at 43 and oscillated by a crank 44 and connecting rod 46, the crank being formed on a crankshaft 47 mounted in bearings 48 (see Figure 4) and driven continuously by motor and reduction gear (not shown). The charger 42 forces the clay through a grid 49 which serves to retain a plug of clay, constituting a seal, in the inlet of the chamber 39 thus allowing the space above the general level of the clay in the chamber 39 to be maintained under vacuum, the inlet of the chamber 39 being below the general level of the clay.

Within the chamber 39 the worm shaft 37 is provided with a series of inclined propelling blades 51 serving to force the clay downwardly into the extrusion cylinder 32, and above the uppermost blade 51, there is secured to the shaft 37 a pair of levelling arms 52 terminating in upstanding blades 53, the arms 52 sweeping the clay to a substantially level surface while the blades 53 remove from the wall of the chamber any layer of clay forming there as a vestige of the vortex-like surface tending to form as a result of the rotation of the clay as a whole. The arms 52 and blades 53 are also inclined so as to assist in urging the clay downwardly. A deflector ring 54, formed from angle iron, is fixed to the chamber wall above the level of the blades 53 to deflect inwardly any clay spreading up the chamber wall.

Pivottally mounted in bearings 56 (see Figure 5) formed in the wall of the chamber 39 above the deflector ring 54 is a shaft 57 secured to which is a pair of feelers 58 arranged on opposite sides of the shaft 37, the feelers being about two inches wide and resting freely on the surface of the clay formed by the levelling arms 52 so as to rise and fall with variations in the level of the surface.

The movement of the feelers serves to operate a pneumatic servo-mechanism controlling the

amount of clay fed to the hopper 41 in a manner which will now be described with particular reference to Figures 4, 5 and 6.

Secured to one end of the shaft 57 protruding from the chamber 39 is an arm 59 to the extremity of which is pivotally attached one end 61 of a telescopic valve-operating rod 61, 62, arranged to actuate a valve 63, the two parts 61 and 62 of the rod being connected by a tension spring 64 (see Figure 8) serving as a safety device in case of excess movement of the feelers 58. The valve 63 controls the supply of compressed air from a pressure line 65 to a double-acting pneumatic cylinder 66 controlling the operation of the plough 22 mentioned above with reference to Figure 1. The plough 22 is pivotally mounted at 67 on a framework 68, serving to support the conveyor 19 at a higher level than the feed hopper 41, the free end of the plough being supported on a guide plate 69 by means of a projecting lip 71. The cylinder 66 is pivotally attached at 72 to the framework 68 while its piston rod 73 is pivotally attached at 74 to the plough 22.

The valve 63 also controls the supply of compressed air to another double-acting cylinder 76 pivotally attached at 77 to a bracket 78 extending from the hopper 41, its piston rod 79 being pivotally attached at 81 to a gate 82 pivotally mounted at 83 on the discharge end of the chute 21 immediately above the hopper 41, the gate serving to retain a reserve of clay in the chute. The valve 63 and cylinders 66 and 76 are of known construction and are generally indicated diagrammatically in Figure 8.

The apparatus described in this example, however, is intended for the manufacture of socketed pipes, the extrusion being interrupted as each pipe is formed and removed from the extrusion press. The feeding of clay, therefore, roughly coincides with the extrusion of each pipe.

As soon as extrusion is interrupted (or the feed to the hopper becomes excessive, therefore, the continued feeding of clay to the chamber 39 causes the levelling arms 52 to lift and move the valve 63 into reverse position (the valve being moved in this case through the tension in the spring 64), thus causing air from the pressure line 65 to pass through an air line 87 to the closed ends of the cylinders 66 and 76 to cause the plough 22 to move into its inoperative position and the gate 82 to close. Whilst, in this example, the charger 42 operates continuously, therefore, the supply of clay to the hopper 41 is cut off and no clay is fed to the chamber 39. In the event that the levelling arms lift excessively, e. g. by a sudden increase in the feed of clay, the excess movement of the arm is allowed by increased extension of the spring 64, thus preventing damage to the valve 63.

Figure 7 shows an extrusion press in all respects similar to that described above except that the clay is forced through the grid 49 by a modified form of feed mechanism (indicated at 14 in Figure 1). In this case, the clay is delivered by the chute 21 directly to the inlet of a feed hopper 88 in which is rotatably mounted a feed worm 89 rotation of which forces the clay through the grid 49 into the chamber 39. The worm 89 is driven by bevel gearing 91, 92 and belt gearing 93 from the drive shaft 34, and the feeding operation thus takes place only when the machine is extruding, the worm 89 stopping with the drive shaft 34.

In operation, as the clay is extruded from the cylinder 32 by the extrusion worm 31, the general level of the clay in the chamber 39 falls, thus

causing the feelers 58 to pivot by gravity and turn the arm 59 to operate the valve 63 (the telescopic rod 61, 62, being fully closed during this movement), such operation of the valve admitting air from the pressure line 65 to an air line 86 leading to the piston rod ends of both cylinders 66 and 76 thus causing the plough 22 to move from its inoperative position (shown in chain-dotted lines in Figure 6) into the path of the clay on the conveyor 19, and the gate 82 to open as indicated by chain-dotted lines in Figure 4. Clay is thus swept from the conveyor 19 into the chute 21 to replenish that allowed to flow into the hopper 41 by the opening of the gate 82. As the clay falls into the hopper 41, it is forced through the grid 49 by the oscillating charger 42 into the chamber 39 to replenish the clay extruded by the worm 31. The chute 21 is inclined at a steep angle, say 45° to 55° to allow the clay to slide freely down the chute, and to preserve a substantially uniform coefficient of friction, the chute is formed from non-rusting material, e. g., stainless steel. The chute is also open-topped to prevent possibility of jamming when a large quantity of clay is discharged by the plough 22. The upper (wider) end of the chute is enclosed, however, to allow oil mist to be sprayed in for lubrication purposes.

It will thus be seen that while extrusion continues, clay is automatically fed to the hopper 41 from the conveyor 19 and the chamber 39 is replenished. The worm 31 is thus kept fully packed without excess height of clay in the chamber 39, and the rate of extrusion thus kept to its highest value for the particular type of machine.

The apparatus in this example is intended for manual control, the drive shaft 34 being operated through a clutch 94 in response a control lever 96 (see Figure 9). The clay feed is again controlled by pneumatic servo-mechanism operating in response to the feelers 58, but the servo-mechanism is also responsive to the clutch control lever 96. The pneumatic mechanism is of known construction and is diagrammatically represented in Figure 9.

As before, the shaft 57 carrying the feelers 58 is provided with an external arm 97 pivotally connected to a telescopic piston rod 98 arranged to operate a valve 99 controlling the supply of air from a pressure line 101 to the cylinder 66 operating the plough 22. In addition to the valve 99, however, a further valve 102 is operable by the clutch control lever 96 to direct air from the pressure line 101 to a further cylinder 103 arranged to operate the clutch 94. The valve 102 also controls the supply of air from the pressure line 101 to a further cylinder 104 arranged in parallel with the cylinder 103 and controlling the position of an abutment member 106 contained in a slotted member 107 attached to the piston rod 108 of the cylinder 104 and embracing the arm 97.

Assuming the apparatus to be stationary, extrusion is commenced by moving the control lever 96 (to the left in Figure 8) to operate the clutch 94, whereupon air is admitted to the closed ends of the cylinders 103 and 104 through an air line 109 thus engaging the clutch 94 and moving the abutment member 106 clear of the arm 97 to allow the feelers 58 to fall and operate the valve 99 which moves the plough 22 into operative position. With the abutment 106 clear of the arm 97, the feelers are free to rise or fall and the operation of the valve 99 is thus dependent on the level of the clay in the chamber 39.

When extrusion ceases (and with it rotation of the feed worm 39) by operation of the control

lever 96 (to the right in Figure 9), air is directed by the valve 102 through an air line 111 to the piston rod ends of the cylinders 103 and 104 to de-clutch the drive shaft 34 and move the abutment member 106 into engagement with the arm 97 so as to cause it to pivot and operate the valve 99 which thereupon admits air from the pressure line 101 to the closed end of the cylinder 66 through an air line 112, thus moving the plough 22 into its inoperative position. When the clutch 94 is disengaged, therefore, the feelers remain inactive.

Whilst the above examples have been described with reference to intermittent extrusion, it will be understood that the invention is equally applicable to continuously extruding presses.

What we claim is:

1. Method of controlling the feed of stiff clay to a vertical extrusion cylinder in which a body of clay is progressed downwardly, said method comprising feeding clay into the upper end of the body of clay, sweeping the free upper surface of the body by a circular motion to bring it substantially level, feeling the level to which the upper surface has been brought, and varying the rate of feed of clay in response to variation in level of said surface.

2. Method as in claim 1, comprising diverting clay from a continuous stream in granular form towards the cylinder in response to a fall in the level of the surface, restraining a quantity of the diverted amount externally of the cylinder on a rise of the level above a predetermined amount, and releasing the restrained quantity for immediate feed into the cylinder on a fall in the level.

3. Mechanism for controlling the feed of stiff clay to a vertical extrusion cylinder, comprising at least one arm adapted to be rotated about the axis of the cylinder so as to form a substantially level surface on the body of clay in the cylinder, a feeler member adapted to rest on the surface so as to rise and fall in response to variation in the level of the surface, and means for varying the rate of feed of clay to the body in accordance with the rise or fall of the feeler member, more clay being fed as the feeler member falls and less clay being fed as the feeler member rises.

4. Mechanism as in claim 3, comprising a feed hopper, a grid between the hopper and the cylinder, a side opening in the cylinder registering with the grid, and means to force the clay from the hopper through the grid into the cylinder in the form of a plug to constitute a seal.

5. Mechanism as in claim 4, comprising an oscillating charger as the means for forcing clay through the grid.

6. Mechanism as in claim 4, comprising a rotatable worm as the means for forcing clay through the grid.

7. Mechanism as in claim 3, wherein the blade of the arm is inclined so as to assist in urging the clay downwards in the cylinder.

8. Mechanism for controlling the feed of stiff clay to a vertical extrusion cylinder in which an extrusion worm is mounted on a vertical rotatable shaft, comprising at least one arm secured to said rotatable shaft above the worm so as to form a substantially level surface on the body of clay in the cylinder, a feeler member adapted to rest on the surface so as to rise and fall in response to variation in the level of the surface, and means for varying the rate of feed of clay to the body in accordance with the rise

or fall of the feeler member, more clay being fed as the feeler member falls and less clay being fed as the feeler member rises.

9. Mechanism for controlling the feed of stiff clay to a vertical extrusion cylinder in which an extrusion worm is mounted on a vertical rotatable shaft, comprising at least one arm secured to said rotatable shaft above the worm so as to form a substantially level surface on the body of clay in the cylinder, a feeler member formed with a pair of feelers extending on opposite sides of said shaft and adapted to rest on the surface so as to rise and fall in response to variation in the level of the surface, and means for varying the rate of feed of clay to the body in accordance with the rise or fall of the feeler member, more clay being fed as the feeler member falls and less clay being fed as the feeler member rises.

10. Mechanism for controlling the feed of stiff clay to a vertical extrusion cylinder comprising at least one arm adapted to be rotated about the axis of the cylinder so as to form a substantially level surface on the body of clay in the cylinder, a feeler member adapted to rest on the surface so as to rise and fall in response to variation in the level of the surface means for feeding clay towards the cylinder, and a servo-mechanism responsive to movement of the feeler member and serving to control the amount of clay fed to the cylinder, by rendering the feed means alternately operative and inoperative.

11. Mechanism for controlling the feed of stiff clay to a vertical extrusion cylinder, comprising at least one arm adapted to be rotated about the axis of the cylinder so as to form a substantially level surface on the body of clay in the cylinder, a feeler member secured to a shaft pivotally mounted across the upper portion of the cylinder, the feeler member being arranged to rest on the surface so as to pivot said shaft in response to variation in the level of the surface, an operating arm secured to said shaft outside the cylinder, and a servo-mechanism responsive to movement of said operating arm serving to control the amount of clay fed to the cylinder.

12. Mechanism for controlling the feed of stiff clay to a vertical extrusion cylinder in which an extrusion worm is mounted on a vertical rotatable shaft, comprising at least one arm secured to said rotatable shaft above the worm so as to form a substantially level surface on the body of clay in the cylinder, a feeler member adapted to rest on the surface so as to rise and fall in response to variation in the level of the surface, a hopper feed leading to the cylinder, a feed worm rotatably mounted in the hopper and adapted to feed the clay into the cylinder, means for varying the rate of feed of clay to the hopper in accordance with the rise or fall of the feeler member, a clutch controlling the rotation of the extrusion worm and the feed worm, a servo-mechanism for operating the clutch, and means connecting said servo-mechanism to the feeler member to render that member inoperative when the clutch is disengaged.

13. Mechanism for controlling the feed of stiff clay to a vertical extrusion cylinder, comprising at least one arm adapted to be rotated about the axis of the cylinder so as to form a substantially level surface on the body of clay in the cylinder, a feeler member adapted to rest on the surface so as to rise and fall in response to variation in the level of the surface, a conveyor arranged to feed the clay in granular form continuously to-

wards the cylinder, a hopper feed leading to the cylinder, a chute leading from the conveyor to the hopper feed, a plough movable across the conveyor and adapted to divert clay from the conveyor into the chute, a movable gate controlling the flow of clay from the chute into the hopper feed, and a servo-mechanism responsive to movement of the feeler member and adapted upon such movement simultaneously to operate the plough and the gate, the closing of the gate restraining a quantity of clay available for immediate feed into the cylinder upon subsequent opening of the gate.

14. Mechanism for controlling the feed of stiff clay to a vertical extrusion cylinder, comprising at least one arm adapted to be rotated about the axis of the cylinder so as to form a substantially level surface on the body of clay in the cylinder, a feeler member secured to a shaft pivotally mounted in the upper portion of the cylinder, the feeler member being arranged to rest on the surface so as to pivot said shaft in response to variation in the level of the surface, an operating arm secured to said shaft outside the cylinder, an endless conveyor arranged to feed the clay continuously towards the cylinder, a hopper feed leading to the cylinder, a chute leading from the conveyor to the hopper feed, a plough movable across the conveyor and adapted to divert clay from the conveyor into the chute, a movable gate controlling the flow of clay from the chute into the hopper feed and when closed restraining a quantity of clay for immediate feed to the cylinder upon subsequent opening of the gate, an air cylinder adapted to control the movement of the plough, a further air cylinder adapted to control the movement of the gate, and a valve responsive to movement of said operating arm and controlling the supply of compressed air to both of said cylinders whereby the plough and the gate are operated simultaneously upon movement of the feeler member.

15. Mechanism for controlling the feed of stiff clay to a vertical extrusion cylinder, comprising at least one arm adapted to be rotated about the axis of the cylinder so as to form a substantially level surface on the body of clay in the cylinder, an upstanding blade on said arm for removing from the wall of the cylinder any layer of clay tending to form there as a result of the rotation of the clay as a whole, a feeler member adapted to rest on the surface so as to rise and fall in response to variation in the level of the surface, and means for varying the rate of feed of clay to the body in accordance with the rise or fall of the feeler member, more clay being fed as the feeler member falls and less clay being fed as the feeler member rises.

16. Mechanism as in claim 15, comprising a deflector ring secured to the cylinder wall above the level of the blade.
